UNITED STATES PATENT OFFICE.

DAVID C. OATMAN, OF BUFFALO, AND FRANK G. CURVIN, OF MEDINA, NEW YORK,
ASSIGNEES, BY DIRECT AND MESNE ASSIGNMENTS, TO FREDERICK F. CHURCH,
OF ROCHESTER, NEW YORK.

WINDSHIELD CLEANER.

1,414,578.

Specification of Letters Patent. Patented May 2, 1922.

Application filed April 16, 1920. Serial No. 374,293.

To all whom it may concern:

Be it known that we, DAVID C. OATMAN, a citizen of the United States, residing at Buffalo, in the county of Erie and State of New York, and FRANK G. CURVIN, a citizen of the United States, residing at Medina, in the county of Orleans and State of New York, have invented certain new and useful improvements in Windshield Cleaners; and we do hereby declare the following to be a full, clear, and exact description of the same, reference being had to the accompanying drawings, forming a part of the specification, and to the reference numerals marked thereon.

The present invention relates to demountable window cleaners adapted particularly for use on either open or closed motor cars. One object of the present invention is to provide means whereby the cleaner may be applied and removed from its support, and also to provide a simplified clip for holding the window cleaner, which is adapted to fit different thicknesses of windows or the frames therefor.

To these and other ends the invention consists in certain improvements and combinations of parts, all as will be hereinafter more fully described, the novel features being pointed out in the claims at the end of the specification.

In the drawings:

Figure 1 shows the preferred embodiment of our invention that is adapted for use on open cars.

Figure 2 shows a modification of the present invention which is adapted for use on closed cars.

Figure 3 represents still another species of the same general type and for the same general use as that shown by Figure 1, but slightly different structurally.

Figure 4 illustrates the method by which the wind shield cleaner of Figure 2 may be demounted.

Figure 5 is a perspective view of the clip. Similar reference characters throughout the several views indicate the same parts.

The principal features of our device are not only its simplicity of construction but the facility with which it may be applied to and removed from the support in which it is mounted, thus permitting its use upon the windows or wind shields of motor cars whether open or closed.

In the present embodiment of the invention, the bar 4 carrying the usual wiper 3 of rubber or similar material is provided at its upper end with a bearing portion 5, preferably formed by bending the bar at an angle, so that it will pass from the front to the rear of the glass 1 to be cleaned, and may be connected with the operating handle 8.

The support for the device shown in Figure 1 is an integral metal clip 10 having the depending and yieldable ends embracing the frame 2 secured in position by a thumb screw 11, having a winged operating end 12, and engaging the lower edge of the frame. The apertures in the clip through which the portion 5 extends are so arranged relative to the top of the frame 2 that the part 5 has a bearing thereon, thus serving to steady the device. In Figure 2, the frame 2 is provided with apertures which form the bearing support, and in Figure 3 the different form of holding clip is provided embodying depending spring arms 15 and 16 which simply hug closely against the frame, the bearing apertures being formed in the bracket or clip above the frame.

In order that the device as a whole may be readily removed from and applied to its support, whether this is of the form shown or is merely an aperture formed directly in the glass itself, the handle 8 is made of material, as a rod, not greater in diameter than the bearing aperture, and preferably pivoted at 9 to the rear end of the bearing portion 5, the end of the portion 5 being reduced or formed into a tongue 6, and the end of the arm 8 being preferably bifurcated and extended beyond the pivot as at 7. 13 indicates washers encircling the part 5 of the device and between them is located a spring 14 operating to press one in contact with the inner side of the supporting member and the other against the portions of the arm 8 extending above and below the pivot 9. This arrangement not only serves to press the wiper 3 in yielding contact with the glass and also holds it in any position of rotary adjustment regardless of the thickness of the supporting medium for the bearing portions, but as the rear washer engages the arm 8 on both sides of its pivot, the arm is maintained in the position shown.

In order to apply the device to the support, the arm 8 is brought into alinement

with the portion 5, the washers and spring slipped off the end of the arm and the parts drawn out as shown in Figure 4. To apply the device a reversal of this process takes place, the washer next the arm 8 being of course moved far enough from the pivot to permit the end 7 of the arm to clear it.

It is understood that this invention is not limited to mounting the window cleaner 10 from a clip or frame, but that the bearing portion 5 is capable of being mounted in other locations and supporting media old in the art. Neither is the bearing portion 5 restricted to rotative movement in its support but may be adapted for other motions old in the art for such bearing portions.

We claim as our invention:

1. A window cleaner comprising a bearing portion, a wiper and an operating handle attached to and movable into alignment with the bearing portion for insertion or removal of the cleaner from a support.
2. A window cleaner comprising a wiper, an operating handle therefor and a bearing portion arranged at an angle to the wiper, said handle being pivoted to the bearing portion, whereby it may be aligned with the bearing portion for insertion or removal of the window cleaner from its mounting.
3. A window cleaner which comprises a wiper, an operating handle and a bearing portion, the operating handle being movable relatively to the bearing portion for alignment therewith whereby the window cleaner 35 may be positioned or demounted by axially

moving the bearing portion and aligned handle.

4. The combination with a support, of a window cleaner comprising a wiper having a bearing portion axially and rotarily movable in the support, a handle pivoted to the bearing portion and movable into axial alignment therewith, a resilient member arranged between the support and handle and holding the wiper in contact with the window to be cleaned.

5. The combination with a support, of a window cleaner comprising a wiper, an operating handle, a bearing portion arranged in the support between them, said handle being pivoted to the bearing portion and adapted to be moved into alignment therewith, and a resilient member engaging the handle on opposite sides of its pivot and cooperating with the support to hold the wiper in engagement with the window.

6. The combination with a support of a window cleaner comprising a wiper, an operating handle, a bearing portion arranged in the support between them, said handle being pivoted to the bearing portion and adapted to be moved into alignment therewith, and a resilient member arranged between the handle and support and holding the wiper in contact with the window to be cleaned when used with supports of different thickness.

DAVID C. OATMAN.
FRANK G. CURVIN.
